Primary Examiner — Shawn T Gingrich

(57) **CLAIM**

The ornamental design for a leak current detection and interruption plug, substantially as shown and described.

DESCRIPTION

FIG. 1 is a top perspective view of the present embodiment; FIG. 2 is a top view of the present embodiment; FIG. 3 is a bottom view of the present embodiment; FIG. 4 is a right view of the present embodiment; FIG. 5 is a left view, of the present embodiment; FIG. 6 is a front view of the present embodiment; and, FIG. 7 is a rear view of the present embodiment. The broken lines in the drawings illustrate portions of the leak current detection and interruption plug that form no part of the claimed design.
